UNITED STATES PATENT OFFICE.

THOMAS M. QUIGLEY, OF LOGANSPORT, INDIANA.

DESIGN FOR A DISPLAY-CASE.

SPECIFICATION forming part of Design No. 29,083, dated July 19, 1898.

Application filed June 10, 1898. Serial No. 683,134. Term of patent 3½ years.

To all whom it may concern:

Be it known that I, THOMAS M. QUIGLEY, a citizen of the United States, residing at Logansport, in the county of Cass and State of Indiana, have invented and produced a new and original Design for Display-Cases, of which the following is a specification, reference being had to the accompanying drawing, forming part thereof.

10 This invention relates to display-cases used in the sale of goods.

The design is clearly illustrated in the accompanying drawing, in which a perspective view of the case is shown.

15 The leading feature of my design is a case or receptacle having its front face open and having an inward-projecting edge around the opening and two wings arranged to project from the front face.

20 In the drawing, A represents the main portion of the display-case, which is, as shown, open at the top and has all its sides, excepting the front side, closed. The front of the case is open, as shown, excepting for a small portion around the edge of the opening, forming an inward-projecting edge of the opening on all sides thereof. Attached to and projecting from the outer edges of the front ^a of the box are wings, each being of a height corresponding to that of the main portion of the case and being of somewhat less width than the width of the main portion.

Having thus described my invention, what I claim as new, and desire to secure by Letters Patent, is—25 The design for a display-case substantially as herein described and shown.

In testimony whereof I affix my signature in presence of two witnesses.

THOMAS M. QUIGLEY.
